APPARATUS FOR SEPARATING OIL FROM OIL BEARING SANDS AND ROCKS

Filed Feb. 17. 1922

Patented Nov. 20, 1923.

1,475,028

UNITED STATES PATENT OFFICE.

WILLIAM J. REILLY, OF DENVER, COLORADO.

APPARATUS FOR SEPARATING OIL FROM OIL-BEARING SANDS AND ROCKS.

Application filed February 17, 1922. Serial No. 537,200.

To all whom it may concern:

Be it known that I, WILLIAM J. REILLY, a citizen of the United States, residing at the city and county of Denver and State of Colorado, have invented certain new and useful Improvements in Apparatus for Separating Oil from Oil-Bearing Sands and Rocks; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to an apparatus for the separation of the oil from oil-bearing rocks and sand while distilling off the lighter constituents of the oil.

Petroleum oils are known to exist in various places and in different materials, among others, in what is commonly known as "oil sands." These oil sands have been found in large amounts on this continent, but so far they have not, to my knowledge, been made use of to any considerable extent for the production of oil in commercial quantities, owing, in all probability, to the fact that the proper method and apparatus for successfully separating the oil from the sand has not been produced.

It is the object of this invention to produce an apparatus by which the oil may be effectively and cheaply separated from the oil sands or rock, and while such separation is going on, to distill off the lighter constituents of the oil.

This apparatus operates on substantially the same principle as that described and claimed in my copending application, Serial Number 537,199, filed February 17, 1922.

In order to more clearly describe my invention, I shall have reference to the accompanying drawing, in which

Fig. 1 shows a side elevation of my apparatus, with parts thereof shown in section;

Fig. 2 is a section taken on line 2—2, Fig. 1; and

Fig. 3 is a section taken on line 3—3, Fig. 1.

The same reference characters will be used to indicate the same or similar parts throughout the several views.

Numeral 1 represents a cylindrical member, which I shall refer to hereinafter as

the "still." Member 1 has a conical lower end portion 2 and an upper end 3 which is preferably spherical in shape. The ends of cylindrical member 1 are each provided with an outwardly projecting flange 4 which may be formed from an angle iron. The ends 2 and 3 are riveted to these flanges, proper gaskets being provided if they are found to be essential. To the upper end 3 there is attached a safety valve 5 and a vapor conductor pipe 6 which is provided with a valve 7; this pipe leads to a condenser, not shown. Within the still I provide a framework having vertical supporting elements 8, to which brackets 9 are secured and suitably spaced apart. A bearing 10 is located centrally of the cylinder and held in place by bars 11 which connect with supporting elements 8. Resting on the lowermost of the brackets 9 is a bearing 12, which is provided on its upper surface with a ball raceway 13, and at its center with a bushing 14. Rotatably mounted in bearing 10 and bushing 14 is a shaft 15 which carries intermediate the two bearings a worm gear 16 which is driven from a worm 17 carried by shaft 18. To the upper end of shaft 15 I secure a grinding element 19 whose lower side has a raceway 20 which cooperates with the raceway 13 to hold in place a plurality of balls upon which the grinding element rotates. Located above the grinding element 19 and cooperating therewith is a second grinding element 21 which is secured by means of adjustable bolts 22 to the uppermost set of brackets 9. Grinding element 21 is provided centrally thereof with an opening 22 to which is secured a short length of pipe 23. Secured to the cover 3 and having its lower end telescopically connected to the upper end of pipe 23 is a second pipe 24, which extends some distance above the cover 3 and is provided with valves 25 and 26. To the top of pipe 24 is attached a hopper 27 which is adapted to receive the material which is to be fed to the still. The still is designed to be operated under pressure and in order to feed material thereinto without permitting the vapors or gases to escape, the lower valve 25 is closed, after which the upper valve 26 is opened; this permits the oil-bearing material to flow down from hopper 27 and fill the space between the two valves. Valve 26 is then closed and oil is transferred from the still through pipe 28 by means of a

pump or injector 29. The oil which flows through pipe 28 mixes with the material and heats the same; lower valve 25 is now opened and the material flows downwardly 5 through pipes 24 and 23 and enters the space between the grinding elements 19 and 21, the former of which rotates. The material which passes through the grinding means has its larger particles broken up, 10 and as they leave the grinders they fall through the oil to the bottom of the still, from which they flow into one of a plurality of separator tanks which I will now describe.

15 Secured to the bottom 2 are two or more pipes 31, each provided intermediate its ends with a valve 32. The lower end of pipes 31 each connect with the upper end 33 of separator tank 30, which is filled to the point 20 indicated by line 34 with hot water. The lower end 35 of the separators 34 is conical and has attached thereto a pipe 36 which is provided with a valve 37 for the purpose of cleaning the tanks. Each tank is also provided at its top with a pet cock or valve 38, by means of which air may be admitted when the tank is being drained and cleaned. In operation, one of the valves 32 is closed and the other is open. The material that 30 comes from the grinders and falls on the bottom 2 will pass through the open valve 32 and into the hot water of the separator, where the oil will be removed therefrom in a manner similar to that by which the fat is 35 separated from meat by boiling water. When the separator is full valve 32 is closed, and the corresponding valve of another separator opened. The full separator is then emptied through valve 37.

40 Near the bottom of each separator there is a pipe 39 provided with a valve 40 for the purpose of supplying water thereto. Within the still and below the grinding mechanism which I have described above, there is 45 a heat coil 41 through which steam or other heated gases or fluids are passed for the purpose of heating the oil and causing a circulation thereof. The upper end of coil 41 is provided with an automatic excess and 50 non-return valve 42, and the lower end with an automatic check valve 43, by means of which the fluid is automatically prevented from entering the still in the event of a failure of the coil 41. Below the coil 41, 55 and opening substantially centrally thereof is a steam pipe 44 which is provided with a valve 45. The oil within the still is maintained at the level indicated by line 46. In order to enable a workman to enter the still 60 for the purpose of cleaning or repairing the same, I provide two manholes 47. A pipe 48 provided with a valve 49 is provided near the bottom of the still for the purpose of removing the excess oil.

65 The operation of my still and separator

is as follows: Material is fed from hopper 27 into the still in the manner above explained. The still is first filled to the level indicated by line 46 and steam under pressure admitted to coil 41, thereby raising the 70 oil to the desired temperature and pressure. The grinding element 19 is rotated by the means described, and the material is crushed and ground and at the same time thoroughly mixed with hot oil, after which it leaves the 75 grinders and drops through the hot oil to the bottom 2 from which it continues through a pipe 31 into one of the separators 30, and here it becomes immersed in the hot water which separates the oil from the solid 80 particles, as the particles which enter the oil are usually of a temperature much higher than that required to boil the water, at the pressure under which the still works, steam will be generated and this will pass 85 upwardly into the still where it will assist in the liberation of the light oil vapors of distillation and produce a more desirable condensate. The heat imparted to the oil in the still will cause the lighter oils of 90 the gasoline series to vaporize, and these vapors will pass through pipe 6 into a suitable condenser. If I desire to do so, I may employ such temperatures and pressures as to bring about the distilling off of the 95 hydrocarbon series that are lower than the gasoline series to produce oils of the gasoline series, this practice being referred to by the oil refining trade as "cracking." When gasoline is obtained by simple distillation or 100 from the vapors of the lower series by "cracking," I may add to the charge of oil a suitable amount of barium chloride, anhydrous aluminum chloride, or other catalyzing agent which experience has shown 105 hastens the reaction.

From the above it will appear that I have designed a simple and convenient apparatus by means of which the oil carried by oil sands or oil-bearing rocks may be separated 110 from the solid matter, and at the same time the oil will be subjected to a distilling process by means of which the lighter oils are removed therefrom. As my apparatus can be operated at any desired degree of temperature and pressure, it may also be employed for the distilling off of the vapors of a lower hydrocarbon series known as "cracking."

Having now described my invention or 120 discovery, what I claim is—

1. An apparatus for separating oil from oil-bearing rock, comprising in combination, a vertically arranged substantially cylindrical still member adapted to contain 125 oil, a supporting framework within said still, a pair of bearings supported by said framework, a shaft rotatable in said bearings, means for rotating said shaft, a grinding element non-rotatably secured to the 130

- upper end of said shaft, a second grinding element rigidly secured to said framework, means for introducing the oil-bearing rock to said still and between said grinding elements, and a heating coil located within said still below said grinder. 45
2. An apparatus for separating oil from oil-bearing rock, comprising in combination, a vertically arranged substantially cylindrical still member adapted to contain oil, a supporting framework within said still, a pair of bearings supported by said framework, a shaft rotatable in said bearings, means for rotating said shaft, a grinding element non-rotatably secured to the upper end of said shaft a second grinding element rigidly secured to said framework, means for introducing the oil-bearing rock to said still and between said grinding elements, means for contacting said material with heated oil before it enters the grinder, a heating coil located within said still, said coil having its axis vertical, and a steam pipe opening into the still below said heating coil. 50
- 10 15 20 25
3. An apparatus for separating oil from oil bearing rock, comprising in combination a vertically arranged, substantially cylindrical still member adapted to contain oil, a supporting framework within said still, a pair of bearings supported by said framework, a shaft rotatable in said bearings, means for rotating said shaft, comprising a worm gear secured thereto, a grinding element non-rotatably secured to the upper end of said shaft a second grinding element rigidly secured to said framework, means for introducing the oil bearing rock to said still and between said grinding elements, means for contacting said material with heated oil before it enters the grinder, a heating coil located within said still and below said grinder, a steam pipe opening into the still below said heating coil, a plurality of separator tanks connected to said still, and valve means between each of said tanks and said still. 60
- 30 35 40
4. An apparatus for separating oil from oil bearing rock, comprising in combination a vertically arranged, substantially cylindrical still member adapted to contain oil, a supporting framework within said still, a pair of bearings supported by said framework, a shaft rotatable in said bearings, means for rotating said shaft, comprising a worm gear secured thereto, a grinding element non-rotatably secured to the upper end of said shaft a second grinding element rigidly secured to said framework, means for introducing the oil bearing rock to said still and between said grinding elements, means for contacting said material with heated oil before it enters the grinder, a heating coil located within said still, said coil having its axis vertical. 70
- 75 80 85
5. An apparatus for separating oil from oil bearing rock, comprising in combination a vertically arranged, substantially cylindrical still member adapted to contain oil, a supporting framework within said still, a pair of bearings supported by said framework, a shaft rotatable in said bearings, means for rotating said shaft, comprising a worm gear secured thereto, a grinding element non-rotatably secured to the upper end of said shaft a second grinding element rigidly secured to said framework, means for introducing the oil bearing rock to said still and between said grinding elements, means for contacting said material with heated oil before it enters the grinder, a heating coil located within said still, said coil having its axis vertical, a steam pipe opening into the still below said heating coil, a plurality of separator tanks connected to said still, and valve means between each of said tanks and said still. 85

In testimony whereof I affix my signature.

WILLIAM J. REILLY.
